[57] CLAIM

The ornamental design for an automobile tire, as shown and described.

DESCRIPTION

FIG. 1 is a perspective view of an automobile tire showing our new design, it being understood that the tread pattern is repeated throughout the circumference of the tire, the opposite side being substantially the same as that shown;

FIG. 2 is an end-elevational view thereof; and

FIG. 3 is a side-elevational view thereof.

FIG. 1

FIG. 2

FIG. 3
